UNITED STATES PATENT OFFICE

2,519,885

CONVERTIBLE CHAIR

Charles Carlson, Kirk's Mills, Pa.

Application May 4, 1948, Serial No. 25,652

5 Claims. (Cl. 155—1)

1

The present invention relates to a chair of simple, compact construction which can be made to be utilized in any one of three useful positions without involving any mechanical adjustments or relative movements of the several parts thereof and merely by changing the relative position of the chair as a whole with respect to the floor or ground on which it is positioned.

The chair of the present invention can be made either with or without arm rests which latter can be one or more pairs of stationary arm rests or can be adjustable arm rests which can be moved from one to another of the three positions of the chair, in cooperative relation to the seat thereof. In the illustrated embodiment of the chair of the present invention an adjustable arm rest is shown.

The embodiment of the present invention shown and described herein as an illustrative example, the various parts thereof are arranged with respect to each other to provide, in one position, a chair, which gives a relatively upright back rest with the latter sloping slightly backwardly to afford a restful position; in another position to define a more sloping back to afford a reclining position; and in another position of the chair to provide an elongated seat, as in a chaise longue, with the back thereof sloped to the reclining position and, at the end of the elongated seat away from the back thereof, a support member which can be utilized as a shade for a person sitting in the chair when it is used in the relatively upright position and this support member (or shade) can be fixedly or foldably mounted to the chair.

In the accompanying drawing forming part of the present disclosure:

Figures 1 and 2 are respectively, side and perspective views of the chair of the present invention in the upright position;

Figures 3, 4 and 5, are respectively, front, side and perspective views of the same chair in the reclining position;

Figures 6 and 7, are respectively, side and perspective views of the same chair in the elongated chair position; and

Figure 8 is an elevation view, in part cut away, of an adjustable arm rest of the chair and securing means therefor.

In the embodiment of the chair of the present invention illustrated in the accompanying drawing a relatively long, medially extending element of board 1 carries fixed thereto, at a point intermediate the middle and one end, a relatively short element or board 2 which extends outwardly

2

from one face of said long board 1. In the side view shown in Figure 1 of the drawing said shorter board 2 can be seen to define an angle of less than ninety degrees with the lower and short end or portion 3 and an obtuse with the upper, long end or portion 4 of said long board 1, and said short board 2 is at a substantially horizontal position, with said lower short end or portion 3 resting on the floor or other support 5. Adjacent to said shorter board 2 but on its opposite face said long board 1 carries a second short element or board 6 which extends outwardly from said long board 1 at an angle with long portion or end 4 greater than the angle 10 defined by said short board 2 and the opposite face of said long board 1 and downwardly, in the position of Figure 1, to serve as a floor engaging support member cooperating with said lower portion or end 3, to hold in substantially upright position the chair defined by these recited elements and as shown in Figure 1, with said short element or board 2 serving as the seat and said long end or portion 4 adapted to serve as a back. See also Figures 2 and 3. In 15 Figures 4 and 5 the relative positions of the elements in Figure 1, described above, are changed with respect to said floor 5 whereby said short end or portion 3 and said short element or board 2 cooperate as floor engaging support members 20 to hold the defined chair in a reclining position, with said second short element or board 6 serving as a seat and said long end or portion 4 adapted to serve as a back.

Toward the outer end of said long portion 4, 25 said long board is cut out on both sides along lines parallel to the sides thereof to define a narrower portion 7 which carries, in rotative relation thereto and one on each side thereof, a pair of support members 8, 8, between which latter there extends from one to the other, and fixedly connected thereto, a cross member 9 on the side or surface of said support members 8, 8 away from said short board or element 2 whereby cross member 9 and said support members 8, 8 can be folded downwardly (in Figure 1) to bring said cross member 9 against said long board 1 and said support members 8, 8 alongside said narrow portion 7. In the open or unfolded position shown in Figure 1 said support members 8, 8 and said cross member 9 define a rotatively adjustable shade for a person sitting in the chair in the position illustrated in Figure 1.

In Figures 6 and 7 is illustrated an elongated chair position of the chair of the present invention in which said support members 8, 8 and

said cross member 9 are opened or unfolded to bring the inner edge of said cross member 9 against the face of said long board 1 with the ends of said support members 8, 8 in chair supporting engagement with the said floor 5 in cooperation with said short board or element 2 which also rests with its out end on the floor, and said second short element or board 6 is adapted to serve as a back rest. When the chair of the present invention is in the position illustrated in Figures 6 and 7 it can be used as a litter for carrying an invalid or ill person reclining thereon, said short portion 3 of said long board 1 at that outer end thereof being formed into a pair of handles 10, 10 (see Figure 3) and said support members 8, 8 extend outwardly beyond said cross member 9 to form a corresponding and cooperative pair of handles 11, 11 at the opposite end (see Figure 7).

Said long element or board 1 carries, fixedly mounted with respect thereto and one on each side thereof, a pair of circular members 12, 12 at a place near the junction thereof with first said short element or board 2 and second said short element or board 6, each of which said circular elements 12, 12 carries at its center an outwardly extending bolt 13 on each of which rides a respective thumb-nut 14 and washer 15. Each of said bolts 13, 13 carries a respective strip 16 which extends outwardly beyond the edge of its respective circular member 12 at one of its ends and at its other has a slot 17 which fits over the respective bolt 13, said thumb-nuts 14, 14 being adapted to press their respective washers 15, 15 against said strips 16, 16 in desired predetermined rotative positions. Each of said strips 16, 16 carries at its outwardly extending end an arm rest 18 which can be set, by means of said thumb-nuts 14, 14, in arm rest relation with respect to the seats defined by each of said long board 1, short board 2, and second short board 6 as desired when the chair of the present invention is in any of various positions as illustrated in the accompanying drawing, and the height of said arm rests 18 can be adjusted by moving said strips 16, 16 longitudinally on said bolts 13, 13 as permitted by the sides of said slots 17, 17.

While no specific values have been recited above for the angles at which said short portion 3, short element or board 2 and second short element or board 6 are disposed with respect to one another and no specific or proportional or relative dimensions are given for said short portion 3, short board or element 2 and second short element or board 6 it is considered that the above recited description taken with the drawings to which reference has been made above and which form part of this application is sufficient to enable a carpenter or anyone of similar skill to construct the chair of the present invention.

What I claim as new and useful, and desire to protect by Letters Patent is:

1. A chair adapted to be used in various relative positions of the elements thereof with respect to a supporting floor on which it rests, including a substantially upright position, a reclining position and an elongated seat and litter position, and

comprising a relatively long, medial element, one relatively short portion of which is adapted to serve as a floor engaging support member both in said upright position and in said reclining position and in the elongated seat position is adapted to serve as a litter handle at that end and a longer portion adapted at one face to serve as a back rest in said upright position and adapted at its opposite face to serve as a back rest in said reclining position, and in said elongated seat position is adapted at said opposite face to serve as a long seat; a relatively short element attached to said relatively long, medial element at said one face and at a location between said relatively short portion and said longer portion and adapted in said reclining position to serve as a seat and in both said reclining position and in said elongated seat position to serve as a floor engaging support member, in said reclining position in cooperation with said short portion; a second relatively short element attached to said relatively long, medial element at said opposite face and at a location between said relatively short portion and said longer portion and adapted in said reclining position to serve as a seat, in said elongated seat position to serve as a back rest and in said upright position to serve as a floor engaging support member in cooperation with said short portion; and a third relatively short element, attached to said longer portion of said relatively long, medial element near the outer end thereof and adapted to extend outwardly from said one face thereof to serve in cooperation with first said short element as a floor engaging support element; said second short element forming an angle with said longer portion greater than the angle formed by first said short element and said longer portion.

2. The chair of claim 1 and in which first said relatively short element is shorter than said second short element.

3. The chair of claim 1 and in which said third short element defines a shade substantially above first said short element when said chair is in said substantially upright position.

4. The chair of claim 1 and in which said third short element is foldable against said long, medial element.

5. The chair of claim 1 having a pair of arm rests, one on each side of said chair, rotatably adjustable into operative arm rest positions respectively at each of said substantially upright, reclining and elongated seat positions.

CHARLES CARLSON.
